CONTROL HEAD PACKER

Raymond G. Taylor, Jr., and Donald B. Hooser,
 Dallas, Tex., assignors to The Guiberson Cor-
 poration, Dallas, Tex., a corporation of Dela-
 ware

Application December 31, 1941, Serial No. 425,080

4 Claims. (Cl. 166—12)

1

This invention relates to control head packers and constitutes an improvement over the type of control head packer shown in the patent to Albert Pranger, Patent No. 2,227,912, issued January 7, 1941.

So far as we know, all control head packers heretofore invented have a mandrel which is provided with a shoulder or collar or the equivalent, and which acts as a part of the recovery means to lift the slip head when it is desired to remove the packer from the well. Obviously, such mandrels were expensive to manufacture, and if it were necessary to replace the mandrel, such as to provide a shorter or a longer mandrel to vary the amount of opening or the distance between the valve and the valve seat of the control head packer, such an exchange would be an expensive one, probably involving not only a new mandrel but many other parts. In fact, the construction of control head packers heretofore made has practically prohibited an exchange of parts to vary the extent of the opening of the control head valve. In our improved construction, our mandrel consists of a simple pipe having no recovery shoulder or the equivalent thereon. Instead, our recovery means does not form a part of the mandrel, but forms a part of the gudgeon coupling which is screwed to the mandrel. In order, therefore, to vary the amount of opening of the control head valve, it is only necessary to insert a new pipe of a different length from the one which is being replaced, and by selecting the proper length pipe, the extent of opening of the control head valve can be adjusted quickly and at minimum expense.

Another object of the invention is the provision of a mandrel having an unobstructed exterior, except for a retaining shoulder to limit the amount of expansion of the packing element for the valve itself.

Another object of the invention is to connect the recovery sleeve directly to the slip head so that said parts move as a unit, the recovery sleeve being directly connected and engaged when the mandrel is raised by a shoulder on the gudgeon coupling.

Still another object of the invention is to provide the gudgeon pin on the coupling detachably secured to the mandrel and to the well tubing.

Another object of the invention is to provide an improved packing means corresponding to the sleeve packing element 23 of the said Pranger Patent 2,227,912 and providing that packing element with reinforcements.

Another object of the invention is to provide 55 a shoulder 20 on the mandrel 1 and interposed between the lower portion of the coupling 16, and the upper surface of the ring 5 is an elastic sleeve packing element 4 provided with spaced apart circum-

2

an improved control head packer which is simple in construction and extremely efficient in operation.

Other objects and advantages of the invention will appear in the detailed specification and claims which follow.

Referring to the drawings, in which the perfected embodiment of the invention is shown by way of illustration.

Figure 1 is a vertical elevational view of our improved packer, certain of the parts being shown in cross section and showing the relative position of the parts when the packer is being run into the well.

15 Figure 1A is a similar view and constitutes a continuation of Figure 1, being the parts below what is shown in Figure 1.

Figure 2 is a view similar to Figure 1, but showing the relative position of the parts when the 20 packer is set in the well.

Figure 2A is a view similar to Figure 1A and showing the relative position of the parts, shown in Figure 1A, when the packer is set in the well.

Figure 3 is a cross-sectional view on the line 25 3—3 of Figure 1.

Figure 4 is a cross-sectional view on the line 4—4 of Figure 1A.

Figure 5 is a cross-sectional view on the line 5—5 of Figure 2.

30 Figure 6 is a cross-sectional view on the line 6—6 of Figure 1, and

Figure 7 is a side-elevational view of the mandrel and the parts screwed on the upper and lower ends of said mandrel.

35 The invention may be better understood by referring to the drawings in detail, in which a packer mandrel 1 is provided at its upper end with screw threads, to which is secured a coupling 16 which couples the mandrel to the flow line or tubing 17 extending to the top of the well. The coupling 16 is provided with the valve 3 adapted to engage a valve seat 18 on the upper end of a sleeve 19.

40 A shoulder 20 is provided on the mandrel 1 and serves as a limit to the downward movement of the ring 5, which is slidable through a bore 21 of the sleeve 19 and which is adapted to seat on a shoulder 22 at the lower portion of the bore 21, which shoulder 22 constitutes a valve seat. The

45 ring 5 is slidable on the portion of the mandrel 1 above the shoulder 20, and interposed between the lower portion of the coupling 16, and the upper surface of the ring 5 is an elastic sleeve packing element 4 provided with spaced apart circum-

ferentially extending steel rings 14, having in-

wardly extending feet 15 adapted to contact the outer surface of the mandrel. A packing corresponding to our elastic sleeve packing element 4 was shown in the said Pranger Patent 2,227,912, but without the reinforcing rings above mentioned.

When the packer is being set, as will herein-after be described, the ring 5 would first contact the shoulder 22 and further downward movement of the mandrel would compress the elastic sleeve packing element 4 so as to effectively seal the bore 21, and thereafter the valve 3 would contact the valve seat 18 so that we have a double valve and with a sleeve packing element between the two valves.

The mandrel 1 below the shoulder 20 is simply a plain piece of pipe which is screw threaded at its lower end and receives a confined gudgeon coupling and recovery ring 2 provided with a gudgeon pin 12 and with centering vanes 23. This gudgeon coupling 2 is screw threaded at its lower end and is adapted to be connected with a downwardly extending flow line.

A sleeve 10 is slidably mounted on the mandrel and is directly secured to the slip head 6 by means of bolts 24. This sleeve 10 is the recovery sleeve and is provided at its lower end with a surface or shoulder 9, which is adapted to be contacted by the upper shoulder 8 of the gudgeon coupling, when the packer is being pulled out of the well, thereby elevating the slip head 6, so that the slips 7 are retracted in the well-known manner. The shoulder 8 is sometimes referred to in the claims as a recovery shoulder. The slips 7 are connected by reins 25 to the anchor cage 11, to which is secured the upper ends of springs 26, adapted to contact the inner surface of the casing 27. The lower ends of the springs 26 extend into slots 28 in bosses 29 on the lower portion of the anchor cage 11. Below the bosses 29 is the slot 13 having a valley 30 in which the gudgeon pin 12 rests when the packer is being run into the well.

The recovery sleeve 10 is provided with a shoulder 31 underlying a shoulder 32 of the anchor cage 11. When the packer is being run in the well and as the mandrel moves downwardly carrying the coupling 2 and gudgeon pin 12, the said pin engages the valley 30 of the cage 11, pulling the said sleeve and springs 26 downwardly, and the shoulder 32 engaging the shoulder 31 moves the sleeve 10 and slip head 6 downwardly, all of the said parts moving as a unit. Since the slips 7 are connected to the cage 11, it is impossible for the slips to engage the casing.

The sleeve 19 is threaded to a downwardly extending sleeve 33 provided with a shoulder 34 underlying a shoulder 35 of a sleeve 36 secured to the slip head 6 by means of bolts 37. A lower retaining ring 38 rests on the upper end of the sleeve 36 and is slidable on the sleeve 33. A casing packing element 39 is interposed between the lower portion of the sleeve 19 and the upper portion of the ring 38. The sleeve 36 is provided with openings or holes 40 extending from the interior of the well casing below the casing packing element 39 into a passageway 41. The slip head 6 is provided with a passageway 42 communicating with the interior of the well casing below the casing packing element and with the said passageway 41. A passageway 43 extends between the sleeve 33 and the mandrel and connects the passageway 41 to the bore 21.

The operation is very simple. When the parts

are in their running-in position, as shown in Figures 1 and 1A, and the mandrel is lowered, the cage 11, springs 26, sleeve 10, slips 7 and slip head 6 move downwardly as a unit, so that the slips cannot engage the casing, as heretofore described. As the slip head 6 moves downwardly, it carries the sleeve 36, and its shoulder 35 engages the shoulder 34 of the sleeve 33, which is directly connected to the upper sleeve 19, so that all of said parts move downwardly as a unit. The valve 3 is prevented from moving towards the valve seat 18, and the valve ring 5 is prevented from moving towards its seat 22, so that the said valves are positively maintained open and well fluid can by-pass between the outer periphery of the packer 39 and the well casing as well as upwardly through the by-pass 43, so that ample passageways are provided so that the well fluid can by-pass the casing packing element when the parts are being lowered into the well.

When it is desired to set the packer, the mandrel is raised slightly so as to lift the pin 12 from the valley 30, and it is then rotated to the right, as viewed in Figure 1A, so as to clear the lower portion of the slot 13. The mandrel is then lowered into the position shown in Figure 2A. The cage 11, being no longer pulled downwardly by the pin 12, is held stationary by the springs 26 engaging the well casing. As the mandrel is moved downwardly, after the pin 12 is released from the slot 13, the valve ring 5 would engage its seat 22 and further downward movement of the packer would compress the elastic sleeve packing element 4, sealing the bore 21, and the valve 3 would engage its valve seat 18. The cage 11 would rise upwardly relative to the sleeve 10, because of the downward movement of the sleeve 10, and the slips would be expanded into engagement with the casing, and the casing packing element 39 would be expanded into sealing engagement with the casing, so that all by-passes between the casing packing element and the mandrel, and between the casing packing element and the casing, would be sealed. The parts 2 and 2A.

When it is desired to remove the control head packer from the well, the mandrel is lifted so that the recovery shoulder 8 engages the shoulder 50 9 of the sleeve 10, thereby positively elevating the slip head 6 and retracting the slips 7 from engagement with the well casing. The shoulder 31 of the sleeve 10 now engages the shoulder 32 of the cage 11, to which is attached the springs 55 26, so that the springs and cage 11 thereafter move upwardly with the mandrel. The valve 3 moves away from its valve seat 18 and the valve ring 5 moves away from its seat 22 thereby opening the by-pass extending from the bore 21 through the passageways 43 and 41 and through the passageways 40 and 42, so that fluid above the packer need not be lifted. As the slip head 6 moves upwardly, it, of course, moves the sleeve 36 and lower ring 38 upwardly so that the entire assembly can be moved to the surface of the well, while the fluid above the packer can by-pass downwardly around the sleeve. Attention, in particular, is called to the fact that the mandrel 1 is simply a plain piece of pipe, except for the small shoulder 20 thereon, and is provided with screw threads at each end. If the operator desires to shorten the distance between the valve 3 and the valve seat 18, all that it is necessary for him to do is to unscrew the man-

drel 1 and insert a shorter one. These mandrels can be very inexpensively manufactured and nothing would have to be changed except the mandrel. Of course, if he desired for it to be a longer distance between the valve 3 and its valve seat 18, he would insert a longer mandrel. Therefore, the operator, by providing himself with various lengths of inexpensive mandrels, can quickly change the extent of opening of the valve. In all other forms of mandrels known to us, there is a recovery shoulder on the mandrel, but our mandrel has no recovery shoulder thereon. The recovery shoulder, instead, is the shoulder 8 of the gudgeon coupling and recovery ring 2.

Having now described our invention, we claim:

1. In combination with a tubing, a mandrel connected in the tubing, a casing packing element, a sleeve slidable on the mandrel and forming a part of a setting means for the casing packing element, and a recovery ring detachably secured to the mandrel and adapted to engage a shoulder on the sleeve when the mandrel is raised while the packing element is in set position.

2. In combination with a tubing, a mandrel connected in the tubing, a casing packing element, there being a by-pass between the mandrel and packer, a valve to open or close said by-pass, a sleeve slidable on the mandrel and forming a part of a setting means for the casing packing element, and a recovery ring detachably secured to the mandrel and adapted to engage a shoulder on the sleeve when the mandrel is raised after the packing element has been set.

3. In combination with a well tubing adapted to be lowered into a well casing, a packer comprising a mandrel connected in the tubing, a casing packing element, a sleeve slidable on the mandrel and forming a part of a setting means for the casing packing element, a cage slidable

5

on the sleeve, casing engaging springs carried by said cage, said cage being provided with a bayonet slot, a recovery ring secured to the lower portion of said mandrel and provided with a recovery shoulder and a gudgeon pin, said gudgeon pin serving as a means to move the cage and springs downwardly with the tubing as it is lowered when the said gudgeon pin is in the valley of the bayonet slot, said shoulder being adapted to engage the lower end of the sleeve and raise the same when the tubing is raised.

10

4. In combination with a tubing string adapted to be lowered and set in a well casing, a mandrel in said tubing string, a casing packing element on said mandrel, a valve on said mandrel to open or close a by-pass between said mandrel and casing packing element, a recovery sleeve slidable on said mandrel, a slip head connected to the recovery sleeve, slips slidable on the slip head to engage or disengage the casing, whereby the sleeve is held stationary relative to the well casing so that the casing packing element is set when the slips engage the casing and the tubing is lowered, a cage slidable on the sleeve and provided with casing engaging springs, reins connecting said slips to said cage, a coupling attached to the lower end of the mandrel, a gudgeon pin and a recovery shoulder forming a part of said coupling, said cage being provided with a bayonet slot to receive the gudgeon pin and serve as a means to force the cage downwardly when the mandrel is lowered, contacting shoulders on the sleeve and cage to pull the sleeve downwardly when the mandrel and cage are lowered, the recovery shoulder on the coupling engaging the lower end of the sleeve and raising said sleeve when the mandrel is raised after the casing packing element is set.

RAYMOND G. TAYLOR, JR.
DONALD B. HOOSEN.
